UNITED STATES PATENT OFFICE.

ARTHUR A. PANNIER, OF SALT LAKE CITY, UTAH.

PRINTER'S GALLEY RACK.

Application filed December 21, 1923. Serial No. 691,990.

To all whom it may concern:

Be it known that I, ARTHUR A. PANNIER, a citizen of the United States, residing at Salt Lake City, in the county of Salt Lake and State of Utah, have invented a new and useful Printer's Galley Rack, of which the following is a specification.

This invention relates to a printer's galley rack, and its principal object is to provide a cabinet of simplified construction containing any number of sections, in which each galley is provided with means engaging and supported by the sides of the compartment in which it is filed, so that each galley acts as its own shelf and the usual shelves are eliminated, thereby economizing space and making it possible to file a greater number of galleys in a cabinet of given size. The same cabinet may also be arranged with shelves which may take the place of the galleys, when it is desired to use all or a portion of the cabinet as a catalogue file, or for similar purposes.

The detailed construction of the invention will be more specifically described in connection with the accompanying drawing, which illustrates the preferred form.

In the drawing:

Figure 1 is a front elevation of one section, constructed according to the invention.

Figure 2 is a sectional view taken on the line 2—2 of Figure 1.

Figure 3 is a fragmentary view showing, in section, the construction of one of the grooves or gains which support the galleys.

Figure 4 is a perspective view of a specially constructed galley to be used in connection with the invention.

Figure 5 is a fragmentary perspective view showing a galley of modified construction.

Referring in detail to the drawing, the numeral 5 indicates a section, any number of which may be joined together after the manner of a sectional bookcase. Each section 5 is rectangular in shape, and forms a compartment between the sides 6, which is of sufficient width to receive the galleys 7 arranged lengthwise. The distance from the front of the cabinet to the back 8 is substantially equal to the width of the galley. The sides 6 of the cabinet section are formed with series of opposed saw cuts, grooves or gains 9, each of which when the cabinet is made of wood is preferably reinforced with a metallic lining 10, which is perma-

nently secured within the gain by burs, as indicated at 11, or other suitable means. When the cabinet is to be used as a galley rack exclusively, the gains preferably slope slightly downwardly toward the back of the cabinet, as shown in Figure 2. The lining is omitted when the cabinet is made of metal.

Each galley 7 is provided with the usual side flange 12 and end flange 13. In order that the galley may be supported in the gains 9 without the interposition of shelves, the flanged end 13 is formed with a rib 14 or similar projection extending horizontally outwardly from the bottom of the galley beyond the end flange 12, while at the opposite end, the bottom of the galley extends at 15 beyond the end of the side flange 12, so that the rib 14 and the extended portion 15 of the bottom slide within the metallic linings 10 and support the galley. Thus, each galley forms its own shelf, and the space usually taken up by the shelves is thereby saved and a greater number of galleys may be filed within a cabinet of given size. The spaces occupied by the successive galleys are preferably numbered, as indicated by the numerals 16, so that if a record is kept the printer can readily lay his hands on any type required.

In the form of galley shown in Figure 4 the projecting rib 14 is formed by folding the projecting end of bottom 7 back upon itself to form the rib and then bending it upwardly to form the flange 13, the rear end of which may be welded to the end of the flange 12, while in the form shown in Figure 5, the flange 13 may be integral with the flange 12, and its lower edge may be turned outwardly and welded to the projecting end of the bottom 7 to form the rib 17.

The same frame can be used for a catalogue file, or for other purposes. In this case, flat pieces of steel may be substituted for the galleys to form shelves, and certain of the shelves may be omitted if it is desired to have more space between the shelves.

While I have shown and described the specific construction of the cabinet in its preferred form, it is to be understood that this is merely illustrative, and that modifications may be made in the size, shape and general arrangement without sacrificing any of the salient features of the invention as claimed.

What is claimed is:

1. A cabinet having a compartment provided at its ends with series of opposed grooves extending from front to rear, a series of cooperating galleys, each having the usual side and end flanges and provided with a guiding rib projecting horizontally outward from the bottom of the galley beyond the end flange, and the bottom of the galley being extended horizontally outward at the other end beyond the end of the side flange, said rib and extended end of the bottom forming guiding means, which are received within said grooves to support the galley within the cabinet, whereby each galley serves as its own shelf within the cabinet.
2. A cabinet having a compartment provided at its ends with series of opposed grooves extending from front to rear, a series of cooperating galleys, each having an upstanding side flange at its rear edge, the bottom of the galley being extended horizontally outward at one end beyond the end of the side flange and doubled back upon itself to form a projecting guiding

rib, and then turned upwardly to form an end flange of substantially the same height as the side flange, the bottom being also extended horizontally outward at the other end beyond the end of the side flange, said rib and last mentioned extended end forming guiding means which are received within said grooves to support the galley within the cabinet, whereby each galley serves as its own shelf within the cabinet.

3. A galley having the usual bottom with end and side flanges, and provided with a transverse guiding rib projecting below the end flange, said rib being formed at the junction of the bottom and end flange and projecting horizontally outward, and the bottom being extended horizontally outward at the other end beyond the end of the side flange, said rib and extended end of the bottom forming guiding means to slidably engage grooves in a supporting structure.

In testimony that I claim the foregoing as my own, I have hereto affixed my signature.

ARTHUR A. PANNIER.
